[57] **CLAIM**

The ornamental design for a garage wall mounted car door protector, as shown and described.

DESCRIPTION

FIG. 1 is a perspective view of my ornamental design for a garage wall mounted car door protector;

FIG. 2 is a perspective view from the other side of my design from FIG. 1;

FIG. 3 is a front elevation view of my design;

FIG. 4 is a rear elevation view of my ornamental design;

FIG. 5 is an end elevation view of my design as seen from the right end of FIG. 1, also the left end elevation view is a mirror image thereof; and,

FIG. 6 is a section taken through FIG. 4 at line 6—6 to clarify the contours of the rear surface of my design.
